The ornamental design for a fluorescent lamp, as shown and described.

DESCRIPTION

FIG. 1 is a front perspective view of a fluorescent lamp within a reflector, using a two-U tube light unit and having a screw-type base;

FIG. 2 is a side elevational view thereof, with the opposite side being a mirror image;

FIG. 3 is a bottom plan view thereof;

FIG. 4 is a top plan, or front view thereof;

FIG. 5 is a front-perspective view of a second embodiment of the fluorescent lamp within a reflector, and using a three-U tube light unit;

FIG. 6 is a side elevational view of the lamp of FIG. 5, with the opposite side being a mirror image;

FIG. 7 is a bottom plan view thereof; and,

FIG. 8 is a top plan or front view thereof.
